Primary Examiner — Vy Koenig*Assistant Examiner* — Kimberly Barnes(74) *Attorney, Agent, or Firm* — Peter J. Ims; Westman, Champlin & Koehler, P.A.(57) **CLAIM**

The ornamental design for a slat wall, as shown and described.

DESCRIPTION

FIG. 1 is a perspective view of a slat wall;
FIG. 2 is a front view of the slat wall where the front view and the back view are mirror images of each other;
FIG. 3 is a top view of the slat wall, where the bottom view is identical to the top view.
FIG. 4 is a right side view of the slat wall; and,
FIG. 5 is a left side view of the slat wall.
The broken lines shown in the drawings are included for purposes of illustrating portions of the slat wall that form no part of the claimed design.
